United States Patent Office.

DESIGN FOR A TOBACCO PIPE.

GEORGE C. BRITNER, OF PHILADELPHIA, PENNSYLVANIA, ASSIGNOR TO
HARVEY & FORD, OF THE SAME PLACE.

Design No. 2,507, dated November 27, 1866.

SPECIFICATION.

TO ALL WHOM IT MAY CONCERN:

Be it known that I, GEORGE C. BRITNER, of Philadelphia, county of Philadelphia, State of Pennsylvania, have invented or produced a new and original design for a Tobacco Pipe; and I do hereby declare the accompanying drawing, with the following explanation of the same, to form a full, clear, and exact description of the said design.

The figure in the accompanying drawing represents a tobacco pipe; A being the stem, and B a cylindrical cup or reservoir to which the lower end of the stem is connected, and to which is secured the bowl, C; this application for a patent not relating to the shape of the latter. The stem is bent to the form shown in the drawing, and to the upper end of the same is connected the mouth-piece, D.

I claim the design for the part of a tobacco pipe, substantially as shown in and by the accompanying drawing.

In testimony whereof I have signed my name to this specification in the presence of two subscribing witnesses.

Witnesses:

Wm. H. PAUL,
W. J. R. DELANY.

GEORGE C. BRITNER.
